UNITED STATES PATENT OFFICE.

GUSTAVE E. VILLARET, OF LEONIA, NEW JERSEY, ASSIGNOR TO WILLIAM R. NOE & SONS, OF NEW YORK, N. Y., A CORPORATION OF NEW YORK.

DESIGN FOR A FINIAL FOR LIGHTING FIXTURE.

Application filed September 18, 1924. Serial No. 10,815. Term of patent 7 years.

To all whom it may concern:

Be it known that I, GUSTAVE E. VILLARET, a citizen of the United States, residing at Leonia, in the county of Bergen and State of New Jersey, have invented a new, original, and ornamental Design for Finial for Lighting Fixture, of which the following is a specification, reference being had to the accompanying drawing, forming part thereof.

Fig. 1 is a front elevation showing my new design.

Fig. 2 is a bottom view, and is given to show the contour of the fixture.

I claim:

The ornamental design for a finial for lighting fixture, as shown.

GUSTAVE E. VILLARET.
